UNITED STATES PATENT OFFICE.

PHILIP REITER, OF NEW YORK, N. Y.

SAFETY BACK DEVICE FOR EAR ORNAMENTS.

Application filed October 22, 1926. Serial No. 143,455.

The present invention relates to safety-back devices for ear ornaments, and is more particularly directed to a safety-back device peculiarly adapted for use with ear ornaments which extend upwardly from the lobe of the ear.

The more common forms of ear ornaments either hang downwardly from a center of support, or are carried directly on the lobe of the ear. As the center of gravity is not above the center of support, it is only necessary to clamp the ear ornament onto the ear sufficiently tight to prevent the ornament from coming off the ear on account of its own weight. I have found, however, that ear ornaments which extend a substantial distance upwardly from the lobe of the ear cannot be satisfactorily supported by a simple clamping device which grips only a small area in the lobe of the ear.

The present invention contemplates a supporting device which grips the ear at widely separated points, preferably at the lower part of the lobe of the ear and at a point well up onto the main part of the ear, so that the tendency of a long ear ornament extending upwardly from the lobe of the ear to loosen from the ear is resisted effectively without annoying the wearer.

The accompanying drawings show, for purposes of illustration, one of the many possible embodiments in which the invention may take form, it being understood that the drawings are illustrative of the invention rather than limiting the same.

In these drawings:

Figure 1 is a view illustrating the ear ornaments on the ear;

Figure 2 is a longitudinal sectional view of the ear ornament;

Figure 3 is a side elevational view of the ear ornament from the rear; and

Figure 4 is an enlarged fragmentary elevational view of the clamping device taken in the direction of the arrow 4 of Figure 2.

The exposed ornamental part of the ear ornament is indicated at 10. It preferably is a long gracefully shaped ornament of any suitable contour and is provided with jewels or enamel as desired. This ornament extends from the lobe 11 of the ear 12 up along the outer edge of the body of the ear.

A curved strap 13 passes downwardly underneath the lobe of the ear and is carried up behind of the ear as indicated at 14.

This portion 14 of the ornament is spaced a

sufficient distance from the back of the ear to accommodate a movable clamping plate 15. This plate is narrow and approximately as long as the ornament 10. A pair of parallel guiding pins 16 and 17 carried by this clamping plate pass through holes 18 and 19 in the member 14. A clamping screw 20 is threaded into this member 14 and is fastened to the plate or bar 15 so that the plate may be moved back and forth by adjusting the screw. Not only do the pins keep the clamping plate in place to insure substantially parallel movement of this plate but they also prevent the long narrow plate from twisting or rotating relative to the clamping screw. They keep the clamping member from twisting out from behind the ear while the ear ornament is being adjusted in place. The ends of the bar 15 are preferably spoon-shaped as indicated so that they grip a large area of the ear in a comfortable manner. They are also preferably provided with grooves 21 to grip the ear more securely.

It will be noted that the present safety-back device is one which grips the ear at widely separated points so that there is no tendency of the ornament to slip off the ear. The guiding pins keep the clamping plate in place and insure substantially parallel movement of this plate with respect to the ornament.

It is obvious that the invention may be embodied in many forms and constructions, and I wish it to be understood that the particular form shown is but one of the many forms. Various modifications and changes being possible, I do not limit myself in any way with respect thereto.

What is claimed is:

1. An ear ornament comprising a front ornamental portion adapted to extend from the bottom of the lobe of the ear upwardly a substantial distance, a rear portion adapted to extend underneath the lobe of the ear and upwardly behind the ear, a clamping member, guide pins carried by the clamping member and passing through the rear portion, and a clamping screw carried by the rear portion and acting against the clamping member to force it against the ear, the clamping member being substantially parallel with the front ornamental portion and of extended length whereby it may engage the ear at widely separated points opposite the ornamental portion.
2. An ear ornament comprising a front

ornamental portion adapted to extend from the bottom of the lobe of the ear upwardly a substantial distance, a rear portion adapted to extend underneath the lobe of the ear and 5 upwardly behind the ear, a clamping member, guide pins carried by the clamping member and passing through the rear portion, and a clamping screw carried by the rear portion and acting against the clamp- 10 ing member to force it against the ear, the clamping member being substantially parallel with the front ornamental portion and having forwardly bent rounded ends adapted to engage the ear at widely separated points 15 opposite the ornamental portion.

3. A safety-back device for ear ornaments comprising a member of substantial length normally positioned behind the ear, a long narrow clamping plate in front of the mem- 20 ber and adapted to extend upwardly along the back of the ear, a clamping screw threaded into the member for adjusting the clamping plate, and means for guiding the clamping plate to permit such adjustment 25 and prevent rotation of the clamping plate

whereby it may be maintained behind the ear.

4. A safety-back device for ear ornaments comprising a member normally positioned behind the ear, a long clamping plate in 30 front of the member, guiding pins carried by the clamping plate and passing through apertures in the member, and a clamping screw threaded into the member for adjusting the clamping plate.

5. A safety-back device for ear ornaments comprising a supporting member, a clamp- 35 ing member in the form of a long rigid bar adapted to extend a substantial distance along the ear, the ends of the clamping mem- ber being broad and having spoon-like tips for comfortable engagement with the ear, and a pair of rearwardly extending guiding pins carried by the clamping member and passing through holes in the supporting member for guiding the clamping member toward the ear and preventing its twisting from behind the ear.

PHILIP REITER.
